MACHINE FOR CUTTING FUR-BEARING SKINS

Arthur G. Settel, New York, N. Y.

Application December 7, 1946, Serial No. 714,700

15 Claims. (Cl. 164—61)

1

This invention relates to a machine useful in working up fur bearing pelts and particularly for cutting skins into strips which can be sewed together to produce variations in the size and appearance of the finished skins and make them acceptable for incorporation into scarfs, boas, muffs, capes, coats and other fur articles.

In working skins to produce fur articles, it frequently happens that a particular skin is of the wrong dimension, i. e., it is usually wide, for example, and to produce a garment from such a fur skin would make it entirely too bulky. It has heretofore been proposed that such skins be cut into narrow longitudinal strips and alternate strips sewed together to form two complete furs which are of the same length but, of course, approximately half as wide. Likewise a skin may be lengthened by cutting it diagonally from the center line and offsetting the strips as they are sewed together. The forming of strips has been accomplished by a machine, as revealed in my previous Patent No. 2,174,603 granted October 3, 1939. A drawback of the previous machine was the sticking of the cut skins to the positioning pins, and, therefore, requiring an excessive amount of time to cut fur pelts into the desired strips.

This invention provides a method and a machine whereby it is possible to cut up skins to make them smaller or in effect to produce two furs from a single skin and in another modification to increase the length of furs, i. e., to make a single skin considerably longer than the original skin from which it was prepared.

It is also an object of this invention to provide a means whereby the cutting elements of the apparatus may be maintained at a maximum degree of sharpness.

A further object of the invention is to prevent the adherence of the cut fur to the holding pins.

To obtain these and other related objects, this invention provides an apparatus by means of which all types of skins may be cut up into individual strips of uniform width and any desired dimensions so that they can be sewed together to form acceptable skins useful for the various purposes to which skins are applied.

The invention may be embodied in a number of different forms but is illustrated herein by reference to a preferred embodiment, and in the drawings:

Fig. 1 is a view in side elevation of the machine of this invention;

Fig. 2 is a view in side elevation with parts cut away of the machine of this invention;

Fig. 3 is a view in cross-section taken in the plane indicated by the line 3—3 of Fig. 1 and looking in the direction of the arrows;

Fig. 4 is a fragmentary view in cross-section taken in the plane indicated by the line 4—4 of Fig. 1 and looking in the direction of the arrows;

Fig. 5 is a fragmentary view in cross-section taken in the plane indicated by the line 5—5 of Fig. 3 and looking in the direction of the arrows; and

Fig. 6 is a fragmentary view in cross-section taken in the plane indicated by the line 6—6 of Fig. 3 and looking in the direction of the arrows.

15 The machine of this invention is mounted on a suitable base 10 which may be either a permanent support or one that is mounted for movement about the shop. In any event, the base 10 can be associated with a motor to drive the mechanism in the manner hereinafter to be described. Supported on the base 10 are two side plates 12 and 14, respectively, see Figs. 2 and 3. Carried between the side plates 12 and 14 by means of rollers 16 running in grooves 18 of the side plates 12 and 14 is the table top 20 which is provided with a removable, longitudinally slotted rectangular insert 22 centrally of the table top 20 and carried in grooves 24 of top 20. Extending longitudinally of the slotted plate 22 are spaced slots 23 which may be separated an equal distance all the way across the plate or may be variably spaced. The upper surface of the slotted plate 22 is adapted to receive a skin 26 (see Fig. 4) which may be placed thereon, leather side down and the hair away from the slots.

30 Carried below the slotted plate 22 is a shaft 28 journaled in arms 30 and on which are carried circular knives 32 registering in the slots 23 of the slotted plate 22. The knives 32 are vertically adjustable in order that the knives can be protruded above the slotted plate 22 a distance equal to the thickness of the pelt to be sliced. To this end, the arms are secured to a shaft 36 which is journaled in the side plates 12 and 14 and extends outwardly beyond the side plate 12 so as to carry a second arm 38 which extends in a downward direction.

35 In order to maintain arm 38 at a predetermined position, threaded members 40 and 42 are provided which are screwed into blocks 43 fixed to the frame, and bear against either side of arm 38. By turning member 40 and 42 by means of some tool adapted to register with the heads 44 and 45 on the member 40 and 42, respectively, the arm 38 may be caused to move either to the

left or right as desired (see Fig. 1) and thus raise or lower blades 32.

For the purpose of maintaining the blades 32 as sharp as possible at all times, bullet-shaped stones bear against the cutting edges of the knives 32. As shown in Fig. 6, two stones 46 are provided for each blade and are carried at the ends of spring pressed rods 47 which are mounted in blocks 48. To insure that the stones remain in proper relation to the blades, the blocks 48 are positioned on sliding blocks 49. A threaded rod 50, rotatably secured to a member 51, passes through and engages threads within holes 52 in sliding blocks 49. With right and left-hand threads on the respective ends of the rod 50 a suitable tool acting on the head member 53 of the shaft 50 will cause the stones 46 to move together or away from each other.

In order to maintain the slots in the slotted plate 22 in true alignment, two sets of slotted rollers 54, 55, 56 and 57 are provided at spaced intervals. As shown in Figs. 2 and 3, these rollers 54, 55, 56 and 57 are carried on shafts 59, 60, which are journaled on the upper ends of shaft members 62, 63, 64, 65 (not shown) which are in turn carried in cylinders 68, 67, 63, 69 (not shown). Cylinders 67 and 69, secured to the side plates 12 and 14, are also provided within with springs (not shown) which force the shaft members upward and thereby the rollers 54 and 57 upward to engage the slots in the slotted plate 22. Cylinders 67 and 68 are secured to a bracket 70 which is adjustably mounted on a rod 71 which is mounted below the blades 32 in the side plates 12 and 14 (see Figs. 1 and 2). Rollers 55 and 56 are vertically positioned by set screws 72 located in the bottom of the cylinders 67 and 68 and bear against the lower end of the shaft members 63 and 64.

When the skin or pelt is laid in the proper position on the slotted plate 22, it is held in place by a rectangular member 73 from which extends a plurality of pins, with sharp ends, mounted close together and in rows the length of the rectangular member 73 and which register between the slots of slotted plate 22.

In order to raise and lower the pin board 73, four arms, 82, 83, 84, 85 are provided with rollers 86 which run in tracks 87 and 88 on the top surface of side plates 12 and 14. Arms 82 and 83, as shown in Fig. 3, are keyed to shaft 89 which is journaled in two posts 90 and 91 on respective sides of the pin board 73. Arms 84 and 85 are similarly carried on shaft 92 at the other end of the pin board 73. Centrally of the shafts 89 and 92, arms 94 are keyed thereto and to which crank arms 95 are pivotally mounted at 96, the upper extension of arms 94. Centrally of the pin board 73, rotatably supported in post 99 is a plate 97 to which the crank arms 95 are pivotally affixed in diametrically disposed positions.

As the pelts, especially after being cut, are prone to become fouled in the pins 74, a stripper plate 98 is provided to strip the pins of any entrapped strips of the pelt. The stripper plate is rectangular in form preferably of the same dimensions as the pin board 73 and is provided with a plurality of holes 100 adapted to receive the pins 74. The plate is carried below the pin board 73, the pins 74 passing downward through the stripper plate and is so held by means of bolts 101 which are secured to the stripper plate 98 by means of nuts 102 (see Fig. 5). Bolts 101 pass upward through the pin board 73 and are pro-

vided with a nut 103 at their upper end. A tubular member 104 is secured to the pin board 73 by means of a collar 105 and contains a spring 106 which bears against the collar 105 and the nut 103, thus tending to force the stripper plate upward against the pin board at all times.

To operate the stripper, arms 107 are provided which are keyed to shafts 89 and 92 and extend inwardly therefrom to a position immediately above the bolts 101. The pin board 73 is raised by turning the plate 97 in a clockwise direction, as seen in Figs. 1 and 2, and thereby rotating shafts 92 and 89 in clockwise and counterclockwise direction, respectively. Legs 82 and 83, 84 and 85 move to a vertical position and thereby raise the pin board 73 above the slotted plate. At the same time the arms 107 move downward against the bolts 101 and force them and the stripper plate downward disengaging any parts of the pelt fouled in the pins 74.

On turning the plate 97 in the reverse direction, i. e., counter-clockwise as seen in Figs. 1 and 2, the pin board 73 is lowered and the stripper plate 98 is returned to a position against the underside of the pin board. To insure that the pin board 73 is retained in position on the slotted plate 22, pins 108, placed at the four corners of the pin board and held by means of nuts 109, engage holes 110 within the slidtable table top 20. After having engaged the pelt to be cut between pins 74 and the slotted plate 22, the blades 32 are caused to rotate by a motor suitably placed. The operator pushing on any of the upper structures moves the pin board, the mechanism and the table top 20 longitudinally along the side plates 12 and 14, the protruding knives cutting the leather but not the fur. During the cutting operation, rollers 54, 55, 56 and 57 maintain the slotted plate 22 in perfect alignment.

Various modifications will occur to those skilled in the art in the composition and configuration of the component elements going to make up the invention as a whole, as well as in the uses to which the invention may be put, and no limitation is intended by the phraseology of the foregoing description or illustrations, except as indicated in the appended claims.

What is claimed is:

1. A machine for cutting fur bearing skins comprising a slotted plate for supporting the leather side of a fur bearing skin, opposed means penetrating the fur for holding a skin against the plate at spaced points, means to disengage the skin from the means penetrating the hair, and cutting elements projecting through the slots into contact with the leather side of the fur bearing skin.

2. A machine for cutting fur bearing skins comprising a slotted plate for supporting the leather side of a fur bearing skin, opposed means penetrating the fur for holding a skin against the plate at spaced points, means to disengage the skin from the means penetrating the hair, and cutting elements projecting through the slots into contact with the leather side of the fur bearing skin.

3. A machine for cutting fur bearing skins comprising a slotted plate for supporting the leather side of a fur bearing skin, opposed means penetrating the hair for holding a skin against the plate at spaced points, means to disengage the skin from the means penetrating the hair, and cutting elements projecting through the slots into contact with the leather side of the fur bearing skin.

4. A machine for cutting fur bearing skins comprising a slotted plate for supporting the leather side of a fur bearing skin, opposed means penetrating the hair for holding a skin against the plate at spaced points, means to disengage the skin from the means penetrating the hair, and rotary cutting elements projecting through the slots into contact with the leather side of the fur bearing skin.

5. A machine for cutting fur bearing skins comprising a slotted plate for supporting the leather side of a fur bearing skin, opposed means penetrating the hair for holding a skin against the plate at spaced points, means to disengage the skin from the means penetrating the hair, and rotary cutting elements projecting through the slots into contact with the leather side of the fur bearing skin.

6. A machine for cutting fur bearing skins comprising a slotted plate for supporting the leather side of a fur bearing skin, opposed means penetrating the hair for holding a skin against the plate at spaced points, means to disengage the skin from the means penetrating the hair, and rotary cutting elements projecting through the slots into contact with the leather side of the fur bearing skin.

7. A machine for cutting fur bearing skins comprising a bed plate, a plurality of spaced renitent strips providing slots therebetween forming a support for the leather side of a fur bearing skin, cutting elements projecting through said slots, means positioned above said bed plate engageable with said bed plate to position the skins at spaced points on the renitent strips, and means on the means positioned above the bed plate to disengage the fur bearing skin from the positioning means.

8. A machine for cutting fur bearing skins comprising side plates, a bed plate to support the skin horizontally slideable in said side plates, skin positioning means vertically movable above said bed plate, and arm means pivoted on said positioning means and in movable contact with said side plates.

9. A machine for cutting fur bearing skins comprising side plates, a bed plate to support the fur bearing skin horizontally slideable in said side plates, skin positioning means vertically movable above said bed plate, and arm means pivoted on said positioning means and in rolling contact with said side plates.

10. A machine for cutting fur bearing skins comprising side plates, a bed plate to support the fur bearing skin horizontally slideable in said side plates, skin positioning means vertically movable above said bed plate, arm means pivoted on said positioning means and in rolling contact with said side plates, and means to activate said arm members.

11. A machine for cutting fur bearing skins comprising side plates, a bed plate to support the fur bearing skin horizontally slideable in said side plates, skin positioning means vertically movable above said bed plate, arm means pivoted on said positioning means and in rolling contact with said side plates, means to activate said arm members, and fur stripping means spring carried in said positioning means to strip the fur bearing skins from the positioning means.

12. A machine for cutting fur bearing skins into strips comprising side members, a bed plate to support the fur bearing skins horizontally movable in said side members, pointed means in spaced position on a vertically movable member, spaced strips in the bed plate registerable with the pointed means, and spacer means on the side members to maintain said spaced strips in straight alignment.

13. A machine for cutting fur bearing skins into strips comprising side members, a bed plate to support the fur bearing skins horizontally movable in said side members, pointed means in spaced position on a vertically movable member, spaced strips in the bed plate registerable with the pointed means, and rotary spacer means on the side members to maintain said spaced strips in straight alignment.

14. A machine for cutting fur bearing skins into strips comprising side members, a bed plate to support the fur bearing skins horizontally movable in said side members, spaced strips in the bed plate, and rotary spacer means on the side members to maintain said spaced strips in straight alignment.

15. A machine for cutting fur bearing skins in strips comprising side members, a bed plate to support the skins horizontally movable in said side members, a plurality of renitent strips in said bed plate, pointed skin-positioning means registerable with said renitent strips, shafts on the pointed means, arms pivoted on said shafts and in rolling contact with said side members, actuating means on said shafts, stripping means engaging said pointed means and spring secured thereto, and stripping actuating means on said shafts, said stripping means and said arms being actuated by said actuating means.
